SHOE HEEL

Gayton Dellea, Detroit, Mich.

Application September 14, 1936, Serial No. 100,619

3 Claims. (Cl. 36—38)

This invention relates to shoe heels and the object of the invention is to provide a spring supported cushion heel attached to the shoe and having a screw for adjusting the cushion heel in position and compressing the spring.

Another object of the invention is to provide a shoe heel comprising a recessed member attached to the heel seat of the shoe and having a rubber heel member movable vertically within said recessed member, a spring being positioned between the rubber heel and the recessed member and arranged to allow the spring to compress as the rubber heel is walked on.

A further object of the invention is to provide a shoe heel comprising a rubber heel member having a metal plate embedded therein and provided with a screw extending through said plate and a spring held under compression by the screw so that the rubber heel member is supported on said spring.

A further object of the invention is to provide a shoe heel comprising a recessed member having a central boss and a helical coiled spring having a small end fitting about said boss and a large end engaging a rubber heel member to urge the same outwardly and a screw extending through said rubber heel member and threaded into the recessed member to limit the outward movement of the rubber heel by the spring.

Another object of the invention is to provide a recessed member having a wide groove in the forward edge and a rubber heel member having a metal plate embedded therein and provided with an extending tongue riding in said groove, the said groove in combination with the adjusting screw, limiting outward movement of the rubber heel.

These objects and the several novel features of the invention are hereinafter more fully described and claimed and the preferred form of construction by which these objects are attained is shown in the accompanying drawing in which—

Fig. 1 is a bottom plan view of a shoe heel embodying my invention.

Fig. 2 is a section taken on line 2—2 of Fig. 1.

Fig. 3 is a view similar to Fig. 1 with the rubber heel member removed.

Fig. 4 is a perspective view of the rubber heel member showing the extending tongue of the embedded metal plate.

In Figs. 1, 2 and 3, I have shown a shoe 1 having a sole 2. A recessed member 3 is provided which is attached to the sole 2 by the nails 4 shown in Figs. 1, 2 and 3 and this member 3

as will be understood from Figs. 2 and 3 is provided with a recess 5 into which the rubber heel 6 may fit. This rubber heel 6 is shown more particularly in Fig. 4 and a metal plate 7 shown in Figs. 1 and 2 is embedded in the rubber heel 6. 5 This metal plate 7 is provided with a series of apertures 8 through which the rubber of the rubber heel extends when the plate is embedded therein. This metal plate 7 is provided with an aperture 9 at the center as will be understood 10 from Figs. 2 and 4 and a screw 10 is fitted through this central aperture 9 and threaded into the recessed member 3 which is provided with a boss 11 about the screw. This boss 11 is circular in form as shown in Fig. 3 and is provided with a central threaded aperture 12 there-through for the screw 10.

The heel, as shown in Figs. 2 and 4, is provided with an extending tongue 14 which is the forward edge of the embedded metal plate 7 and 20 this tongue 14 extends into a wide groove 15 provided therefor in the forward wall of the member 3 as will be understood from Figs. 1, 2 and 3. The rubber heel 6 is supported on a helical coiled spring 16 which is arranged so that upon complete compression it is flat and the central coil of this spring is fitted about the circular boss 11 in the bottom of the recessed member 3. The outer coil or greater diameter of the spring engages against the underside of the rubber heel 30 member 6 and this spring tends to force the rubber heel member outwardly thus holding the embedded plate 7 in firm engagement with the underside of the screw head 10. Upon walking on the rubber heel, as will be understood from Fig. 2, the rubber heel is pushed toward the bottom of the recessed member 3 thus compressing the spring 16 and moving the embedded plate 7 away from the head of the screw 10. At the same time, 35 the tongue 14 may ride up or down in the wide groove 15. By adjustment of the screw 10 the pressure on the spring 16 may be varied to accommodate the heel for use with persons of greater or less weight within certain limits and 40 heavier or lighter springs 16 may be used for persons of extremely heavy or light weight so that the adjustment of the screw 10 will produce the proper resilient action desired by the wearer.

In assembling the device, the spring 16 is first 50 positioned about the boss 11, at which time, the heel is inserted at an angle so that the tongue 14 is engaged into the groove 15, at which time, the screw 10 may be inserted through the central aperture in the plate 7 and threaded into the 55

aperture 12 in the recessed member 3 to the desired adjustment.

In this connection it will be noted that the rubber heel is provided with a recess 17 for the head of the screw 10 which is greater in depth than the thickness of the screw head so that the screw head will not contact the pavement on which the wearer is walking. The recessed member 3 may be formed of cast aluminum or any other desired material having sufficient strength and rigidity and it will be noted that in assembling the device that after the tongue 14 has been engaged in its groove the turning of the screw 10 will bring the outer edge of the heel into the recess with the tongue 14 acting as a fulcrum against the bottom of the groove 15. This action leaves the rear edge 18 of the heel free to act against the spring 16 so that maximum cushioning effect is obtained on this edge which is the initial part of the shoe to contact the pavement. While the heel may rock on the screw 10 as it is being walked upon, it is to be noted that the tongue 14 prevents the forward edge of the heel from being pushed out of the recess 5 when the rear edge 18 of the heel is stepped upon. Also due to the fact that the heel may rock on the spring, the heel is free to adapt itself to any type of walking without wearing crooked or unevenly. It is to be noted that the spring takes the wear away from the rubber heel in that the spring cushions the heel and absorbs a large portion of the wear and shock to the heel.

From the foregoing description it becomes evident that the device is very simple and efficient in operation, will not easily get out of order, may be used with springs of different strength and provides an adjustment to give the desired flexibility for the individual wearer.

Having thus fully described my invention, its utility and mode of operation, what I claim and desire to secure by Letters Patent of the United States is—

1. In a shoe heel, a recessed member adapted for attachment to a shoe, a rubber heel movable vertically in the recessed member, a metal plate embedded in the rubber heel and having an extending tongue, one wall of the recessed member being grooved to receive said tongue and the

groove being of sufficient width as to allow vertical movement of the rubber heel and tongue in the recessed member, a circular boss in the bottom of the recessed member having a threaded aperture therein, a helical coiled spring fitting about the said boss at the small end and engaging the rubber heel at the large end, the rubber heel being provided with a recess at one side of the metal plate and a screw extending through the metal plate and threaded into the threaded aperture in the boss, the recess in the rubber heel being arranged to receive the head of the screw and preventing the screw head from engaging the pavement.

2. In a shoe heel, a recessed member adapted for attachment to a shoe, a rubber heel movable vertically in the recessed member, a metal plate embedded in the rubber heel and having an extending tongue, the recessed member having a straight wall spaced from the rear edge of the shoe and the wall being grooved to receive said tongue, a circular boss in the bottom of the recessed member having a threaded aperture therein, a helical coiled spring fitting about the said boss at the small end and engaging the rubber heel at the large end, a screw extending through the metal plate and threaded into the threaded aperture of the boss and being arranged to place the spring under compression, the arrangement being such that the tongue engaging in the groove prevents the forward edge of the rubber heel from being moved out of the recessed member when pressure is applied to the rear edge thereof by walking.

3. In a shoe heel, a recessed member adapted for attachment to a shoe, a rubber heel movable vertically in the recessed member, a metal plate embedded in the rubber heel and having an extending tongue, one wall of the recessed member being grooved to receive said tongue, a helical coiled spring between the rubber heel and the bottom of the recessed member and a screw extending through the plate in the rubber heel and threaded in the recessed member, the arrangement being such that turning up the screw will move the rubber heel into the recessed member and place the spring under compression.

GAYTON DELLEA.
